SNOW SWEEPER

Jess Adrian Blazier, Cleveland, Ohio

Application November 25, 1938, Serial No. 242,348

2 Claims. (Cl. 15—79)

The present invention relates to new and useful improvements in snow sweepers and has for one of its important objects to provide, in a manner as hereinafter set forth, a machine of this character which is adapted to be pushed by a walking operator with a minimum of effort.

Another very important object of the invention is to provide a snow sweeper of the aforementioned character comprising a rotary broom of a novel construction and arrangement, together with novel means for driving said broom.

Still another very important object of the invention is to provide, in a snow sweeper including a wheel supported frame and rotary broom mounted thereon, novel means for rockably adjusting said frame in a manner to adjust the rotary broom relative to the ground.

Other objects of the invention are to provide a snow sweeper of the character described which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a top plan view of a snow sweeper constructed in accordance with the present invention, a portion of the arcuate shield being broken away in section.

Figure 2 is a view in side elevation of the machine.

Figure 3 is a vertical sectional view through the rotary broom and the shield therefor.

Figure 4 is a view in end elevation of the rotary broom.

Referring now to the drawings in detail, it will be seen that the embodiment of the invention which has been illustrated comprises a frame structure of suitable metal which is designated generally by the reference numeral 1. The frame structure 1 includes a horizontal U member 2 having comparatively long and short legs 3 and 4, respectively. The frame structure 1 further comprises transverse and diagonal braces 5 and 6, respectively, extending between the legs 3 and 4.

Vertical bars 7 of suitable metal are rigidly secured on the legs 3 and 4 at intermediate points. As best seen in Fig. 2 of the drawings, the bars 7 extend above and below the legs 3

and 4. Supporting wheels 8 are mounted on the lower end portions of the vertical bars 7. The reference numeral 9 designates a tongue having diverging arms 10 on its forward end portion pivotally secured to the upper end portions of the bars 7. A handle 11 is provided on the rear end of the tongue 9.

Journalled between the free end portions of the legs 3 and 4 of the frame structure 1 is a rotary diagonal broom which is designated generally by 10 the reference numeral 12. The broom 12 includes a shaft 13 having mounted thereon a series of spirally extending sockets 14. Brushes 15 are secured in the sockets 14 through the medium of transversely extending bolts 16. The broom 12 further includes spirally twisted metallic blades 17 which project from the shaft 13.

Metallic plates 18 and 19 are mounted on the braces 5 of the frame structure 1. Mounted on the plate 19 is a suitable stand 20 (see Fig. 2) 20 on which an electric motor 21 is mounted. The electric motor 21 drives a shaft 22 having one end portion journalled in a suitable bearing 23 which is mounted on the plate 18. The shaft 22 drives the rotary broom 12 through a belt and pulley 25 connection 24. The pulleys of the connection 24 may be of any suitable ratio for rotating the broom 12 at the desired speed. An arcuate shield 25 of suitable metal is mounted on the brace member 6 and extends over the rotary 30 broom 12.

Mounted on the rear portion of the frame member 2 is a vertical guide 26 in which a bar 27 is mounted for sliding adjustment. Mounted on the lower end of the bar 27 is a caster wheel 28. The reference numeral 29 designates a hand operated screw which is rotatably mounted on a suitable support provided therefor on the frame member 2, as at 30. The screw 29 is threaded 35 connected to the bar 27 for raising and lowering 40 said bar.

It is thought that the operation of the machine will be readily apparent from a consideration of the foregoing. Of course, the operator grasps the handle 11 for pushing and steering 45 the device. The construction and arrangement of the wheels 8 and 28 is such that the device may be pushed and steered with a minimum of effort. When the electric motor 21 is energized the broom 12 is rotated through the medium of the drive 50 connection 24 from the motor shaft 22. Due to the fact that the rotary broom 12 extends diagonally across the frame structure, the snow is thrown forwardly and to one side of the machine as said machine is pushed over the ground. The 55

blades 17 are adapted to loosen comparatively hard or packed snow and, in addition, materially assist the brushes 15 in throwing the snow to one side. The pivotal connections of the arms 10 to the upper portions of the bars 7, as at 31, permit limited rocking movement of the frame structure 1 relative to the tongue 9 thereby permitting the machine to negotiate irregularities that may be encountered and still function efficiently. There is sufficient looseness or play in the pivotal connections 31 to allow this. Through the medium of the screw 29 the frame structure 1 may be rockably adjusted on the wheels 8 thereby raising or lowering the rotary broom 12 relative to the ground as desired. Of course, the screw 29 raises or lowers the rear end of the frame structure 1 on the caster wheel 28. The motor 21 may be connected with any suitable source of current. If desired, a suitable internal combustion engine may be substituted for the electric motor 21. Of course, the machine may be used for any other purposes for which it may be found adapted, such as for sweeping leaves, or cleaning sidewalks, etc.

It is believed that the many advantages of a snow sweeper constructed in accordance with the present invention will be readily understood and although a preferred embodiment of the device is as illustrated and described, it is to be understood that changes in the details of construction and in the combination and arrangement of parts may be resorted to which will fall within the scope of the invention as claimed.

What is claimed is:

1. A snow sweeper of the character described comprising a supporting structure including a horizontal U member, said U member comprising comparatively long and short forwardly projecting legs, a diagonal broom rotatably mounted between the free end portions of said legs, braces extending between the legs, a motor mounted on said braces, means operatively connecting the broom to said motor for actuation thereby, an arcuate shield for the broom mounted on one of the braces, supporting wheels mounted beneath the U member, and means connected to the frame structure for moving same over the ground on the supporting wheels. 5

2. A snow sweeper of the character described comprising a frame structure including a horizontal U member, a broom rotatably mounted between the legs of said U member, vertical bars rigidly secured to the legs at intermediate points and extending above and below said legs, supporting wheels journaled on the lower portions of said bars, a tongue including diverging arms pivotally connected to the upper end portions of the bars for pushing the machine over the ground, 20 and a caster wheel mounted for vertical adjustment on the rear portion of the U member and constituting means for rocking the frame structure for raising and lowering the broom. 25
